UNITED STATES PATENT OFFICE.

ARCHIBALD M. WHIPPLE, OF NORTH ADAMS, MASSACHUSETTS.

SYSTEM OF GLAZING.

SPECIFICATION forming part of Letters Patent No. 697,583, dated April 15, 1902.

Application filed January 24, 1901. Renewed September 23, 1901. Serial No. 76,307. (No model.)

To all whom it may concern:

Be it known that I, ARCHIBALD M. WHIPPLE, a citizen of the United States, residing at North Adams, in the county of Berkshire and State of Massachusetts, have invented certain new and useful Improvements in Systems of Glazing; and I do declare the following to be a full, clear, and exact description of the invention, such as will enable others skilled in the art to which it appertains to make and use the same.

My invention relates to an improved system of glazing or securing window-glass in place within a sash, and is designed for either plate-glass work, wherein a single pane is employed, or in millwork or general glazing, wherein a plurality of small panes are used.

The object of the invention is to provide a system or mode of glazing involving mechanical fastening and sealing means of such a nature that the pane or panes of glass will be held securely in place and may be set or reset without the aid of skilled help and without the necessity of working upon the outside of the sash or removing it from the window-frame, and, furthermore, to provide sealing means which shall be neat and ornamental in appearance, form an air and water tight joint, which may be applied and removed without injury in setting or resetting a pane, and which will not be affected by rubbing or cleansing, but will, on the contrary, when pressure is brought to bear upon the exposed surfaces thereof seal the joint more securely and effectively.

A further object of the invention is to provide a system or mode of glazing for mill-sash and general work whereby the panes of glass are firmly held without the use of adhesives and may be inserted and removed from the interior of the building, whereby the ordinary practice of setting the glass prior to use at the sash mill or factory may be avoided and the cost of transportation and liability of breakage of the panes in transit entirely obviated.

A still further object of the invention is to provide an improved sealing-strip for general use which is simple in construction, effective in operation, and is designed to be employed in connection with a bead to secure the glass

without the use of adhesives and to form a close joint.

With these and other minor objects in view, which will appear as the nature of the invention is better understood, the invention consists of certain novel features of construction, combination, and arrangement of parts, which will be hereinafter more fully described, and particularly pointed out in the appended claims, reference being had to the accompanying drawings, in which—

Figure 1 is an inner side elevational view of a window-sash, showing the mode of employing the invention for securing plate-glass in place. Fig. 2 is an enlarged detail horizontal section through one of the side rails of the sash. Fig. 3 is an enlarged detail vertical section through the bottom rail of the sash. Fig. 4 shows two views of a sealing-strip, showing the normal and braided positions of its free fold. Fig. 5 is a view similar to Fig. 1, showing the mode of employing the invention for mill-sash work and general glazing. Fig. 6 is a detail cross-section through a portion of the sash shown in Fig. 5 on the line 6 6 thereof. Fig. 7 is a vertical section through the center munnion on line 7 7 of Fig. 6. Fig. 8 is a detail perspective view of the sealing-strip interposed between the sections of the munnion, and Fig. 9 is a detail view of a strip designed for circular sealing.

Referring now generally to the several figures of the drawings, and particularly to Figs. 1 to 4, inclusive, the numeral 1 designates the stiles, and the numerals 2 and 3 the top and bottom rails, of a window-sash having around the inner edges of said stiles and rails a rabbet, the plane face or shoulder 4 whereof, whereon the glass pane is adapted to seat, is inwardly disposed, so as to adapt the panes to be set and reset from the inner instead of the outer side of the sash, as will be more fully hereinafter described.

In carrying my invention into practice I interpose between the shoulder 4 and glass pane 5 a sealing-strip 6, composed of a body 7, of wood, pasteboard, or any other suitable semi-flexible or elastic material, and an outer metallic covering 8, of tin-foil or any other suitable kind of plastic sheet metal. This cov-

ering 8 is folded longitudinally upon itself to form opposite plies or layers, which are cemented to the opposite sides of the body-strip 6 and are connected at their outer edges by 5 a fold or return portion 9, which, as shown, extends beyond the outer edge of the said body-strip 6 to form a free flexible or plastic portion which is adapted to yield or give under pressure and seal the joints or crevices 10 between the pane and rabbet more securely the greater the pressure brought to bear thereon during the process of washing and rubbing the panes in the cleansing and drying operation. These sealing-strips extend continuously 15 around the rabbet and are cemented or otherwise secured thereto, so as to be held against displacement. The glass pane 5 bears upon the inner side of said strips, which are outwardly disposed, and also upon similar strips 20 laid against the inner side thereof and between the same and the molding strips or beads 10, which are secured to the inner faces of the sash, stiles, and rails and serve to retain the inner series of sealing-strips and the 25 glass pane in position. The sealing-strips upon opposite sides—that is, upon the inner and outer sides of the glass pane—are disposed so that the outer edges of the body-strips or backings thereof lie flush with the 30 outer surfaces of the rabbet 4 and molding-strips 10, with the plastic fold or return portion 9 thereof projecting a short distance beyond said surfaces. From this construction it will be readily seen that in the process of 35 cleansing the glass pane should any pressure be brought to bear upon said sealing-strips the plastic folds or return portions 9 thereof will be braided or forced inwardly, causing said portions to spread to a greater or less 40 degree, according to the amount of pressure brought to bear thereon, and to recede into the crevices or spaces between the pane and the rabbet and molding-strips and more securely and effectually close said crevices or joints to 45 prevent the access of water thereto, whereby an absolutely air and water tight joint is afforded under all conditions of service.

The molding-strip 10 at the bottom of the sash may be and preferably is of a form different 50 from its fellow strips and is preferably inclosed within or covered by a layer 10^a of tin-foil, which may be suitably colored to conform to the color of the remaining strips and sash to provide a neat and tasty appearance, the tin-foil in this connection acting as a water-shed to prevent any moisture or water of condensation flowing down upon the inside of the glass pane from gaining access to the joint between said strip and pane. 55

60 By constructing and arranging the parts in the manner stated I am enabled to secure the largest-sized plate-glass firmly within the sash-frame and to provide an absolutely air and water tight joint.

65 The purpose of arranging the shoulder of the bead 4 to face inwardly instead of out-

wardly, as in the ordinary construction, is to provide for the convenient setting or resetting of the pane from the interior of the sash-frame, thus rendering it unnecessary to perform this work from without or to remove the sash from its frame or casing, and such arrangement also obviates the necessity of first setting the glass plane within its sash before the latter is applied to its frame, whereby all danger of fracture of the pane during the transportation of the sash from the mill or factory to the building to which it is to be applied is entirely avoided. I employ wooden molding-strips and semiflexible or elastic 75 body portions for the sealing-strips in preference to metallic strips, because they are not liable to rot or corrode, are easier secured in position and fitted to form closer joints, and, moreover, possess a certain amount of 80 elasticity with sufficient rigidity to allow the glass pane to have a slight vibratory play under pressure without loosening the fastening connections, whereby liability of fracture of the pane is reduced to a minimum. The 85 wooden strips are adapted also to more closely follow or conform to the irregularities in the panes of glass, so as to render clamping pressure on the glass unnecessary. By constructing and applying the sealing-strips in the 90 manner stated each strip forms a smooth metallic waterproof surface, which effectually hermetically seals the joint and at the same time obviates all liability of warping of the sash parts. The construction also provides 95 a neat and tasty fastening for holding the pane securely without the necessity of springing it and which is adapted to form a yielding cushion, against which the glass may vibrate to a slight extent to reduce the liability 100 of breakage thereof. The sealing-strips may be colored to correspond to the color of the sash or building and keep the surface of the glass clean, as there is no putty to wash off. The fastening is very advantageous, in 105 that it may be easily repaired or renewed without weakening the sash, as the cleavage is perfect, and the sash may be washed or otherwise cleansed without liability of loosening or detaching any of the parts of the fastening, but, on the other hand, with the advantage of making the joint more perfect. Furthermore, the sealing-strip when made of 110 tin-foil forms a practically plated surface, which is bright and attractive and conducive 115 to the entrance of light, and it also makes possible invisible lapping at the corners and gives additional security where the wooden strips meet. By arranging the sealing-strips upon opposite sides of the glass pane it will 120 be readily seen that the pane is cushioned in both directions and that the joints are sealed against the inlet of air or water from without. The manner of applying and removing the pane will be readily understood from the 125 foregoing description, and it will be seen that my improved construction permits of ready 130

insertion and removal of the pane without injury to the sealing or molding strips or to the body of the sash.

In the application of the invention, as shown in Figs. 5 to 8, inclusive, to sashes of that kind provided with one or more pairs of bars or munnions 11 to hold a plurality of panes of glass the construction is essentially the same, except that the munnion 11 is divided, having a fixed portion 11^a, which has its inner face extending flush with the inner face or shoulder of the rabbet 4, and a removable section 11^b, which covers and holds the adjacent edges of the glass pane in place. Upon the inner side or face of the munnion I also provide a sealing-strip 12, composed of an inner ply or layer 13, of pasteboard, leather, wood, or any other suitable semiflexible material, enveloped in a covering 14 of tin-foil, the edges of the tin-foil being extended beyond the ends of the strip 13 to form overlapping portions 15, which are designed to lap over upon the outer sealing-strips of the rabbet. The panes of glass are fitted within the sash in the manner heretofore stated and bear at their meeting edges upon said central munnion-strip 12 and are held in position by screws 16, passed through the said removable section 11^b of the munnion, said strip acting to bear upon the pane to hold it in contact with the said sealing-strip, while the screws act in the nature of stops interposed between the meeting edges of the panes to hold them against movement and properly spaced apart. The advantages of the foregoing construction are that it permits of the ready application and removal or setting and resetting of the panes of glass with ease and facility and without marring the appearance of the sash or injuring the sealing devices. Such construction also permits of the ready setting of the glass within the frame from the interior of the building, which renders it unnecessary to remove the sash from its frame to work upon the exterior of the building or to set the panes of glass within the sash prior to mounting the latter within its frame. As a large proportion of the glass panes in sashes completely fitted at the sash factory or mill are broken while being transported therefrom to the place of use, it will be readily seen that my invention is adapted to effect a great saving in repairs and in the replacing of broken glass and that it is also adapted to prevent loss of heat within a room or apartment, as a broken pane of glass may be quickly removed and a new one substituted therefor without the necessity of lifting the sash out of the sash-frame.

In Fig. 9 I have shown a modification in the form of the sealing-strip to adapt it for angular, circular, or arched sealing, the strip in this case being provided with transverse slits 6^a, extending part way across it, whereby it is adapted to be conveniently bent into the form desired. To provide for the ready bending of the body portion 7^a of the strip, I pref-

erably make such portion of felt; but any other kind of material suitable for the purpose may be employed in lieu thereof.

From the foregoing description, taken in connection with the accompanying drawings, the construction, mode of operation, and advantages of my invention will be readily understood.

Changes in the form, proportion, and minor details of construction may be made within the scope of the invention without departing from the spirit or sacrificing any of the advantages thereof.

Having thus described my invention, what I claim, and desire to secure by Letters Patent, is—

1. A sealing-strip for the purpose set forth, consisting of a body-strip and an outer covering-strip, the latter consisting of a plastic or flexible material enveloping said body-strip, substantially as described. 85

2. A sealing-strip for the purpose set forth, comprising a body-strip, and a covering-strip, the latter consisting of pliable sheet metal 90 folded to envelop said body-strip, substantially as described.

3. A sealing-strip for the purpose set forth, consisting of a body-strip and a covering-strip, the latter being composed of tin-foil bent to 95 inclose said body-strip, substantially as described.

4. A sealing-strip for the purpose set forth, comprising a body-strip and a covering-strip, said covering-strip consisting of a plastic 100 metal shield enveloping said body-strip and having a free folded edge portion adapted when pressed to expand, substantially as described.

5. A sealing-strip for the purpose set forth, 105 comprising a body-strip and a covering-strip, said covering-strip consisting of an outer layer of tin-foil bent or folded to embrace the opposite sides and one edge of said body-strip and having a free outwardly-projecting folded portion for the purpose described.

6. In a system of glazing, the combination of a sash provided with a rabbet having its shoulder inwardly disposed, a glass pane, sealing-strips interposed between the pane and 115 shoulder of the rabbet, molding-strips on the interior of the sash to retain the pane in position, and sealing-strips between said molding-strips and the pane, said inner and outer sealing-strips consisting each of a body-strip 120 having an outer covering-strip of a pliable metal, substantially as described.

7. In a system of glazing, the combination of a sash-frame having a rabbet, a glass pane, molding-strips for retaining the pane in position, and sealing-strips interposed between the shoulder of the rabbet, the molding-strips and the pane, each of said sealing-strips consisting of a body-strip and a covering-strip folded longitudinally upon itself to 130 embrace the body-strip and having a free portion projecting beyond the joint and adapted

when pressed upon to flatten and more effectually close the joint, substantially as described.

8. In a system of glazing, the combination 5 of a sash having a rabbet and a munnion comprising fixed and removable sections, a glass pane adapted to bear upon the shoulder of the rabbet and fixed section of the munnion, molding-strips for holding the pane in position against outward displacement, sealing-strips interposed between the said molding-strips and the pane and between said pane and the shoulder of the rabbet, and fastening devices for securing the removable section 15 of the munnion in position and acting as stops to hold the pane from sliding, substantially as described.

9. In a system of glazing, the combination 20 of a sash formed with a rabbet having its shoulder inwardly disposed, a munnion con-

sisting of a fixed section and a removable section, a glass pane, molding-strips for retaining the pane against outward displacement, sealing-strips between the said fixed section of the munnion, the shoulder of the rabbet and 25 the molding-strips and pane, each of said strips consisting of a body having a covering of plastic metal, such as tin-foil, and fastening devices for holding said removable section of the munnion in position and acting as stops 30 to prevent sliding of the pane in one direction, substantially as described.

In testimony whereof I have hereunto set my hand in presence of two subscribing witnesses.

ARCHIBALD M. WHIPPLE.
